Gerald F. Baldwin

ATTORNEY.

UNITED STATES PATENT OFFICE

PETER CHINIEWICZ, OF DETROIT, MICHIGAN

VENTILATOR

Application filed April 5, 1929. Serial No. 352,629.

This invention relates to improvements in ventilators and refers more particularly to wall ventilators, and aims, among other things to provide one which is simple and relatively cheap to manufacture, and which may be installed either in a building already completed at comparatively slight expense or during actual building.

Another object of the invention is to provide a ventilator having means therein for preventing dust and dirt from passing through.

A further object of the invention is to so divert air passing through the ventilator that it is practically impossible for a strong blast of air to pass through it; and to provide means for opening and closing it that it may be operated by pulling one or other of two cords that depend therefrom.

With these and other objects and advantages in view which will become apparent as the specification proceeds, the invention, which consists in certain novel construction and combination of parts, is hereinafter more fully described with the aid of the accompanying drawings, in which:

Figure 1 illustrates a sectional elevation thereof.

Figure 2 is a partial front elevation.

Figure 3 is a section on the line 3—3 of Figure 1.

Figure 4 is an inverted plan view of the outer end of the air duct.

Figure 5 is a section on the line 5—5 of Figure 1; and

Figure 6 is a section on the line 6—6 of Figure 3.

Referring to the drawings, 1 designates the outer wall of a building, 2 woodwork therein, 3 joists, and 4 the inner wall of a building.

5 indicates the ventilator casing which is adapted to be set in the woodwork 2 between two adjacent joists 3. On the front 45 of the casing is a cover 6 having a central opening 7 therethrough. Over this opening screening 8 is arranged which may be held in position as by an ornamental support 9, so that air may pass freely through the 50 cover 6.

Pivottally mounted on the inner side of the cover 6 is a disc 10 of larger diameter than the opening 7 so that when the said disc is in vertical position air cannot pass through the opening to or from the casing 5. A bracket 11 is also secured to the inner side of the cover 6 and has a central rearwardly projecting portion 11a. On the inner side of the disc 10, usually substantially centrally thereof, an eye 12 is arranged. 13 denotes a spring having one end attached to the eye 12 and its opposite end fastened to the central portion 11a of the bracket 11. It will be noted that the eye 12 and the said central portion 11a are relatively so positioned that the spring 13 always tends to move the disc 10 into the open position indicated at 10a in Figure 1, when the lower end of the cover rests against the back of the casing 5.

To the disc 10 adjacent its lower margin, 70 that is the margin remote from its pivoted portion, a cord 14 is secured, and on cover 6 a spring actuated latch 15 is positioned so that its latch bolt 15a is adapted to engage the lower margin of the said disc. The latch bolt 15a is bevelled at its outer extremity 15b so that when the disc contacts with it when moving into closed position, which is accomplished by pulling the cord 14, the latch bolt moves inwards against the tension of its 80 spring 16 and allows the margin of the disc to pass. To the latch bolt 15a a second cord 17 is attached, when the latter is pulled the bolt moves and allows the disc to be swung into open position indicated at 10a by the 85 spring 13.

Extending outwards from the casing 5 through the outer wall 1 is an air duct 18 which is preferably positioned opposite or above the upper end of the disc 10. This duct has an aperture 19 in the outer end of its underside. The bottom of the duct adjacent the aperture is provided with flexible tongues 20 which engage the lower margin of a screen 21 the upper margin of which 90 latter rests against the vertical end wall of the duct. In this way the screen is made readily removable for cleaning purposes. Within the duct 18 a longitudinal partition 22 may also be provided slidable in slotted 95 100

rivets 23. In this manner incoming and outgoing air passages 24 and 25 are formed.

26 and 27 denote eyelets through the cover 6 for the passage of the cords 14 and 17 respectively.

5 When the disc 10 is in open position air may circulate around its margin into or from the casing and through the duct 18 but owing to the position of the duct relative to the disc it is almost impossible for an unpleasantly strong flow of air to enter through the ventilator. Moreover the provision of the two screens 8 and 21 prevent large particles to pass through the ventilator with the air.

15 While in the foregoing the preferred embodiment of the invention has been described and shown, it is understood that the construction is susceptible to such alterations and modifications as fall within the scope of the
20 appended claims.

What I claim as my invention and desire to secure by Letters Patent is:

1. A ventilator comprising a casing having
25 a cover with an opening therethrough, a duct
extending at right angles to said casing hav-
ing an aperture towards its outer extremity,
a shutter pivotally mounted in said casing
adapted to close said cover opening, means
30 tending to hold said shutter in open position,
a latch on said cover to hold said shutter in
closed position, a cord attached to said shut-
ter and extending through said cover by pull-
ing which said shutter is moved into closed
35 position, and a second cord attached to said
latch and extending through said cover by
pulling which the latch releases said shutter
so that it may be moved into open position
by said shutter opening means.

40 2. A ventilator comprising a casing having an opening therethrough, a shutter pivotal in said casing adapted to close said opening, an air duct having an aperture towards its outer extremity extending from said casing, said duct being so positioned relative to the casing opening and the shutter that air must pass around the margin of the latter when travelling between said duct and said opening, a spring mounted on said casing, 45 and connected to said shutter to move the latter in one direction, other means for moving said shutter in the other direction, and means for holding the shutter in such position that the spring remains in tension.

55 3. A ventilator comprising a casing having a cover with an opening therethrough, a shutter pivotally mounted in said casing adapted to close said cover opening, an air duct having an aperture towards its outer extremity extending from said casing, said duct being so positioned relative to said casing and its shutter that air must pass around the margin of the latter when travelling from said duct to said cover opening, a spring actuated latch on said cover adapted to engage

60

65

the margin of said shutter, means for releasing said latch, means for tending to move said shutter into open position, and means for moving said shutter into closed position.

4. A ventilator comprising a casing, a cover having an opening therethrough, a shutter pivotally mounted in said casing adapted to close said cover opening, an air duct extending substantially at right angles from said casing having an aperture towards its outer extremity, a longitudinal removable partition in said duct, an inwardly removable screen in said duct adjacent said aperture, a spring actuated latch on said cover adapted to hold said shutter in closed position, means tending to open said shutter and hold it in open position, means for moving said shutter into closed position from outside said casing, and means outside said casing for releasing said latch and rendering said shutter opening means operative. 70 75 80 85
